UNITED STATES PATENT OFFICE

169,325

MOISTURE TESTER

Robert R. Moore, Chicago, Ill.

Application April 17, 1951, Serial No. 14,875

Term of patent 14 years

(Cl. D52—1)

To all whom it may concern:

Be it known that I, Robert R. Moore, a citizen of the Dominion of Canada, residing at Chicago, county of Cook, State of Illinois, have invented a new, original, and ornamental Design for a Moisture Tester, of which the following is a specification, reference being had to the accompanying drawing, forming a part hereof.

Fig. 1 is a perspective view of a moisture tester, showing my new design.

Fig. 2 is a side elevation.

Fig. 3 is a front elevation.

I claim:

The ornamental design for a moisture tester, as shown.

ROBERT R. MOORE.
